UNITED STATES PATENT OFFICE.

EDWARD E. STRAUSS, OF CHICAGO, ILLINOIS.

DESIGN FOR A DISPLAY-DESK FOR SAMPLE-BOOKS, SAMPLE-CARDS, AND SWATCHES.

41,863.

Specification for Design.

Patented Oct. 24, 1911.

Application filed July 27, 1911. Serial No. 640,945. Term of patent 7 years.

To all whom it may concern:

Be it known that I, EDWARD E. STRAUSS, a citizen of the United States, residing at Chicago, in the county of Cook and State of Illinois, have invented a new, original, and ornamental Design for a Display-Desk for Sample-Books, Sample-Cards, and Swatches, of which the following is a specification, reference being had to the accompanying drawing, forming part thereof.

Figure 1 is a front elevation of my new design; Fig. 2 is a side elevation thereof; Fig. 3 is a rear elevation thereof.

I claim:

The ornamental design for a display desk for sample books, sample cards and swatches, as shown.

EDWARD E. STRAUSS.

Witnesses:

LOUIS CRIBBERMAN,
BENJ. T. ROODHOUSE.
